HINGE STRUCTURE

Stuart H. Caldwell, Detroit, Mich., assignor to
Christian Giri, Detroit, Mich.

Application March 23, 1936, Serial No. 70,441

5 Claims. (Cl. 16—166)

The invention relates to hinges of that type adapted to be concealed from view when the door is closed while providing for relative movement of the parts thereof about an axis or axes suitable to allow the door to properly clear the body. It is the object of the invention to obtain a simple and efficient construction and to this end the invention consists in the structure as hereinafter set forth.

10 In the drawing:

Figure 1 is a perspective view of the hinge as applied to the door of an automobile shown in open position;

Figure 2 is a plan view through the parts in the 15 closed position;

Figure 3 is an elevation showing the vertical contour of the door and indicating the axis around which the hinge members must turn to give clearance.

As illustrated, A is the post or door jamb and B 20 is the door to be hinged thereto. Secured to the post A is a member C which is of angular form having a portion C' projecting from the inner face of the post and a portion C² which is located in a mortise or recess in the outer face of the post. The portion C' has formed thereon a series of lugs or knuckles D for interconnecting with a pivotal link E which in turn has a knuckle engagement with a second pivotal link F. The portion C² has pivotally connected at the upper 25 and lower ends thereof a pair of levers G and these levers are pivotally connected at H to the link F. Thus, the levers G extend in the general direction of, though not exactly parallel to, the link E and the link F extends transversely to both the link E and levers G in the closed position of the door. The outer end of the link F has a 30 knuckle joint with a bearing I which latter is mounted on the door B and forms a support 35 therefor. The levers G also project into recesses in the door and at their ends slidably engage 40 bearings J, preferably by means of pins K engaging slots L in said bearings.

The mechanism thus far described has the 45 general character of a pantograph, which in the closed position of the door has the link F extending obliquely thereto and to the levers G in a direction towards the hinged edge of the door. When the door is opened, the link E will swing 50 about the center D' of the knuckle D and the levers G will swing about the center C³ of their pivotal connection with the portion C². Also, the link F will swing about the center of the pivot H connecting it to the lever G. Thus, while the 55 door B is moved angularly in relation to the post

A, it is also traveling in the direction of the arrow or away from the pivot center C³ so as to carry its hinged edge outward from the body. The amount of this outward movement may be altered by changing the proportion of the lengths 5 of the links between the pivot centers thereof. Consequently, by suitable proportioning, any desired path of movement for the hinged edge of the door may be obtained, so as to avoid any interference with the body.

As above stated, the mechanism has the general character of a pantograph or four-sided frame with the sides pivotally connected to each other. This frame in the closed position of the door is diamond-shaped, one side being formed 10 by the member C, a second side by the lever G, and the remaining two sides by the links E and F, the link F being extended beyond the lever for its engagement with the door. During the swinging of the door towards open position this 15 frame changes its form by enlarging the two acute angles to obtuse angles and diminishing the two obtuse angles to acute angles. This has the effect of swinging the projecting portion of the link F around the pivot H to produce the 20 outward movement of the door on the lever G, as above described.

What I claim as my invention is:

1. A hinge including a door member, a post member, a pair of load-carrying links pivotally connected to each other and respectively to said post and door members, said links being adapted to be folded and located within a recess in the door in the closed position of the latter, and an auxiliary linkage pivotally connected to said post member and to one of said links and adapted to slidably engage the door substantially in the plane thereof said linkage coordinating the angular movement of the door with the angular movement of said links.

2. A hinge comprising a door member and a post member, a pair of pivotally connected load-carrying links respectively pivotally connected to said door member and said post member, a lever pivoted at one end to said post member and also 45 pivoted to the door connected link intermediate the ends thereof being proportioned to form with said links a substantially diamond-shaped frame in the closed position of the hinge, and means for slidably connecting said lever to the door to hold 50 the same in substantial parallelism in all positions of adjustment.

3. A hinge comprising a door member and a post member, a pair of pivotally connected load-carrying links respectively pivoted to said door 55

- member and post member, a non-load-carrying lever pivoted at one end to said post member being also pivoted to the door connected link intermediate the ends thereof and having a 5 slidable connection with the door and holding the same in substantial parallelism, said links, lever and post member together forming in the closed position of the door a diamond-shaped frame which in the opening of the door has its acute angles enlarged and its obtuse angles diminished thereby moving said door outward upon said links simultaneously with the swinging of said levers about their common pivot axis on said post member.
- 10 5. A hinge comprising a door member, a post member, pivotally connected load-carrying links respectively pivoted to said door member and said post member, and means controlling the movement of said links including guiding means pivotally connected to said post member also pivoted to one of said links and adapted to 15 slidably engage the door, said links and guide means being adapted to be largely located within a recess in said door in the closed position of the latter.
- 15 6. A hinge comprising a door member and a post member, a pair of pivotally connected load-carrying links respectively pivoted to said door member and post member, a pair of non-load-carrying levers embracing said links each being 20 pivotally connected at one end to said post member, being also pivoted to the door connected link intermediate the ends thereof and having

its outer end slidably connected to the door, said links, levers and post member together forming in the closed position of the door a diamond-shaped frame which in the opening of the door has its acute angles enlarged and its obtuse angles diminished thereby moving said door outward upon said links simultaneously with the swinging of said levers about their common pivot axis on said post member.

7. A hinge comprising a door member, a post member, pivotally connected load-carrying links respectively pivoted to said door member and said post member, and means controlling the movement of said links including guiding means pivotally connected to said post member also pivoted to one of said links and adapted to slidably engage the door, said links and guide means being adapted to be largely located within a recess in said door in the closed position of the latter.

20 STUART H. CALDWELL.
